CHAIN LINK PIPE WRENCH WITH PLURAL HANDLE-SAW SURFACES

Robert W. Vose, West Springfield, Mass., assignor to
Moore Drop Forging Company, Springfield, Mass., a
corporation of Massachusetts

Filed Apr. 10, 1959, Ser. No. 805,593

3 Claims. (Cl. 81—68)

This invention relates to pipe wrenches, and particularly to reversible pipe wrenches of the type having a binding chain.

The principal object of this invention is to provide an improved pipe wrench of the above type having constructional characteristics enabling it to be used on pipes of a wide range of sizes with generally uniform gripping action and without any tendency to crush the pipe.

It is another object of this invention to provide an improved pipe wrench of the above type of compact size enabling it to be used in confined spaces.

It is a further object of this invention to provide an improved pipe wrench of simplified construction facilitating its manufacture and enhancing its appearance.

The above and other objects and advantages of this invention will be apparent from the following description and accompanying drawing in which:

Fig. 1 is a fragmentary side elevation of a wrench embodying this invention disposed in operative relation on a length of pipe;

Fig. 2 is a plan view of the wrench;

Fig. 3 is a fragmentary side view of the wrench of Fig. 1, but in different operative relation on the pipe;

Fig. 4 is a diagrammatical showing of the bending stresses on a portion of the wrench under a given load condition; and

Fig. 5 is a diagrammatical showing the manner in which the curvatures of the toothed gripping surfaces are obtained.

Referring in detail to the drawing, a wrench 8 is shown embodying this invention. The wrench is of integral construction and includes a handle portion 10 of generally uniform cross section and a head portion 12 which extends forwardly and is angled upwardly from the handle. The undersurface of the head 12 includes convexly curved gripping surfaces 14 and 16 having oppositely extending teeth for selective forward and reverse rotation of pipe sections such as indicated at 18. A flat link chain 20 is anchored to the shank portion of the wrench by a riveted pin 22 which extends through a hole 23. The chain includes pins 24 which extend laterally outward of the chain. The pins 24 are releasably engageable by hook portions 26 at the outer end of the head 12 to hold the chain about the pipe 18. The chain 20 clamps or binds the pipe 18 to either one or the other of the toothed surfaces 14 or 16, depending on the direction in which the pipe is to be rotated. In Fig. 1 the tooth gripping surface 16 is engaged with the pipe 18 for rotation of the pipe in a counterclockwise direction. In Fig. 3 the gripping surface 14 is engaged with the pipe for rotation in a clockwise direction. A recess 17 is provided between the gripping surfaces affording sufficient clearance to permit the transfer of a pipe from one gripping surface to another without releasing the chain. This recess also permits the chain to be released from the wrench by providing the chain with sufficient slack when the pipe is placed in the recess.

2

The pin 22 by which the chain 20 is anchored to the wrench is located at a point closely adjacent the neutral axis 27 (Fig. 4) of the wrench. Since bending stresses are minimum near the neutral axis of a lever, as illustrated by stress vectors 29 in Fig. 4, the location of the hole 23 closely adjacent the neutral axis 27 has minimal weakening effect on the wrench. It has been thus found unnecessary to provide offsets, webs and other strengthening elements which increase the bulk of the wrench.

10 A pair of flat links 28 are pivotably mounted on the pin 22 on opposite sides of the wrench. The links extend below the undersurface of the wrench and the chain 20 extends from the lower ends of the links 28. The free end of the chain is engageable by the hooks 26 disposed at the forward end of the wrench head. The head 12 is of only slightly greater thickness than the wrench handle 10 enabling the wrench to be used in confined spaces, on short nipples, narrow flanges and the like. Shoulders 30 are disposed forwardly of the pin 22 and 15 engageable by the links 28 limiting the pivotal movement of the links. The toothed surface 14 extends rearwardly of the shoulders 30. This provides relatively long effective pipe gripping surface without consequent increase in the size of the wrench head.

20

25 The outer end of the head 12 is of a bifurcated construction defining a slot 32 adapted to receive portions of the chain link engaged by the hooks 26. Portions of the toothed surface 16 extend beyond the inner end of slot 32. This provides a relatively long gripping surface 30 without consequent increase in the size of the wrench. It will be noted the hooks 26 are disposed well above a line extension of the upper edge of the handle in view of the user facilitating the engagement and ratcheting of the chain by the hooks. The head construction, including 35 the relatively long gripping surfaces 14 and 16 which extend beyond the shoulders 30 and the slot 32, enables the wrench to be used on a wide range of pipe sizes and with a relatively small span of the chain required to bind a pipe against said surfaces.

40 The curvatures of the tooth gripping surfaces 14 and 16 are defined by spirals 34 and 36 shown in Fig. 5. These spirals are of the logarithmic or equiangular type defined by the polar equation $r=ae^{\theta}$ in which $m=\text{arc cotangent of } v$, v is equal to an angle between 60° — 75° , 45 v being defined as the angle the spiral makes with its generating radii, $a=r$ when $\theta=0^\circ$, θ is the polar angle of any point on the spiral, and e is the base of Napierian logarithms. The spirals are symmetrical, having a common point of origin 38 which is located on a straight line 50 40 of a length a from the anchorage pin 22 to the hooks 26. The origin 38 is located a distance b from the anchor pin 22; b equals $\frac{1}{16}a$, the distance from the pin to the hooks 26. The location of the origin 38 and the value of the spiral angle v have been empirically determined to insure generally uniform wrench gripping action for a wide range of pipe sizes. For example, it was 55 found that spirals having an angle v greater than 75° result in gripping surfaces which tend to skid or slip on a pipe. This is particularly so if the teeth are somewhat dulled or if the pipe is of relatively hard material. Spirals having angles v less than 60° have been found too shallow and the gripping surfaces have a tendency to crush pipes under the binding force of the chain 20.

60 This wrench may be conveniently made of an integral steel forging with carburized and hardened teeth. The wrench is relatively light weight consistent with the required strength and has minimum bulk enabling it to be used in cramped quarters. In addition, there is easy accessibility for chain adjustment and adaptability to a wide range of pipe sizes.

Having thus described this invention, what is claimed is:

1. A chain pipe wrench comprising a handle portion,

a head portion extending forwardly of said handle, toothed gripping surfaces of convex curvatures on the undersurface of said head portion for selectively rotating a pipe in forward and reverse directions, a binding chain pivotally anchored on said wrench, said head including means for releasably engaging the free end portion of the chain to bind said chain about a pipe and against one of said gripping surfaces, the curvatures of said gripping surfaces being defined by symmetrical equiangular spirals having a common point of origin located on a straight line extending from the anchorage point of said chain to chain engaging means and $\frac{1}{16}$ the distance from said anchor point to said chain engaging means, each of said spirals forming an angle of between 60 and 75 degrees with its generating radii.

2. A chain pipe wrench comprising a handle portion of generally uniform cross section, a head portion extending forwardly and upwardly of said handle, first and second gripping surfaces of convex curvature on the undersurface of said head extending from the inner to the outer end of said head, said surfaces having oppositely extending teeth, a pipe receiving recess intermediate said gripping surfaces, a binding chain anchored on the shank portion of said wrench adjacent the neutral axis of said handle, said chain including a plurality of outwardly extending pins, the anchored portion of said chain being in the form of a pair of links pivotably mounted on opposite sides of said wrench and extending below the undersurface thereof, said head including shoulder portions engageable by said links to limit their extent of pivotal movement, spaced hooks disposed on the forward upper end portion of said head for releasably engaging the pins on the free end portion of said chain to hold said chain in binding relation about a pipe, and a chain receiving slot in the outer end of said head extending from the top to the bottom thereof, portions of said toothed gripping surfaces extending beyond the inner end of said slot and said shoulder portions, the convex curvature of said gripping surfaces being defined by symmetrical equiangular spirals having a common point of origin located on a straight line extending from the chain anchorage point to said chain engaging hooks and $\frac{1}{16}$ the distance from said anchor point to said hooks, each of said spirals forming

an angle of between 60 and 75 degrees with its generating radii.

3. A chain pipe wrench comprising a handle portion, a head portion extending forwardly and upwardly of said handle, toothed gripping surfaces of convex curvature on the undersurface of said head extending from the inner to the outer end of said head, including oppositely extending teeth for selectively rotating a pipe in forward and reverse directions, a binding chain anchored on the shank portion of said wrench adjacent the neutral axis of said handle, said chain including a plurality of outwardly extending pins, the anchored portion of said chain being in the form of a pair of links pivotably mounted on opposite sides of said wrench and extending below the undersurface thereof, said head including shoulder portions engageable by said links to limit their extent of pivotal movement, spaced hooks disposed on the forward end portion of said head for releasably engaging the pins on the free end portion of said chain, and a chain receiving slot in the outer end of said head extending from the top to the bottom thereof, portions of said toothed gripping surfaces extending beyond the inner end of said slot and said shoulder portions, the convex curvature of said gripping surfaces being defined by symmetrical equiangular spirals having a common point of origin located on a straight line extending from the chain anchorage point to said chain engaging hooks and intermediate said anchor point and hooks, each of said spirals forming an angle of between 60 and 75 degrees with its generating radii.
